UNITED STATES PATENT OFFICE.

WILLIAM H. WOOD, OF CLEVELAND, OHIO, ASSIGNEE, BY MESNE ASSIGNMENTS, TO THE
ASTRUP COMPANY, OF CLEVELAND, OHIO, A CORPORATION OF OHIO.

DOOR-STOP.

1,303,444.

Specification of Letters Patent. Patented May 13, 1919.

Application filed October 15, 1915. Serial No. 56,010.

To all whom it may concern:

Be it known that I, WILLIAM H. WOOD, citizen of the United States, residing at Cleveland, in the county of Cuyahoga and 5 State of Ohio, have invented certain new and useful Improvements in Door-Stops, of which the following is a specification.

This invention relates generally to door stops and particularly to devices of that 10 character utilized upon garage doors and arranged so that the doors may be thrown open and locked in this position, the device holding them until they are released by the user.

More specifically the invention relates to a 15 door holding device and it comprises, in the embodiment shown, a bracket preferably secured to the door lintel and provided with a rod pivotally connected to the bracket and provided at its end with a latch head or 20 member adapted to coöperate with the socket member provided with a latch, the rod being also provided with a yielding stop for insuring the latch operation.

The invention may be further briefly summarized as consisting in the construction and combination of parts hereinafter set forth in the following description, drawings and claims.

Referring to the drawings Figure 1 represents a perspective view of a portion of the door frame and door with the device applied; Fig. 2 is a sectional view showing the details of the latch mechanism; Fig. 3 is a top plan view of the parts showing the door 35 closed with the lintel broken away; and Fig. 4 is a similar view with the door open.

In the embodiment of the invention shown in the drawings, 1 represents a door jamb, supporting in the ordinary way the lintel 2. 40 On the jamb 1 a suitable door 3 is hung.

Secured to the under side of the lintel 2 is a bracket base plate 4 having a downwardly extending post 5, provided with laterally extending arms 6, provided with openings receiving a pivot pin 7. This pivot pin passes through an eye in a head 8, secured to a rod 9. This rod is of a suitable length and is provided near its end with a latch head 10, having an annular latch groove 11 therein, 45 and a tapered portion 12 toward the pivot of the rod. This latch head or member is secured to the rod by means of a pin 13 passing through the parts as shown. Beyond the latch head the rod 9 is threaded as at 14 and 50 is provided with a nut 15 engaging a spring

16 arranged within the sleeve portion 17 and engaging a stop member 18. This stop member slides loosely over the rod 9 and is larger in diameter than the latch head. Secured to the door at the proper points is a 60 latch bracket 19 of any preferred construction and provided with a tubular guide 20. This tubular guide is of a size such that the rod and the latch head may slide freely within the same, but it is less in diameter 65 than the outer diameter of the stop member 18, whereby when the rod and the latch head move through the tubular guide 20, the edge of the sleeve engages the stop member as shown in Fig. 2.

Extending downwardly from the tubular guide is a latch casing 21 having a rectangular chamber 22 for the reception of the latch 23 which is guided in the chamber 22 and is adapted to engage in the groove 11. The 75 latch 23 is provided with a shank 24 extending down through the lower end of the casing 21, and there provided with an opening 25 for receiving a cotter pin 26, which forms a stop limiting the inward movement of the 80 shank 24 and the latch 23. When in their inward position, however, the latch may engage within the recess 11 of the latch head. In order to force the latch into this position a spring 27 is provided surrounding the 85 shank 24 bearing against the latch on the one hand, and against the end of the casing 21 at the other. Secured to the lower end of the shank 24 is a chain 28 which may extend down to a point within easy reach of the 90 user.

When the door is closed the parts are in the position shown in Fig. 3 and the latch head, together with the yielding stop member are out of engagement with the tubular 95 guide and the latch. When the door is open the latch bracket, tubular guide and latch are moved outward in an obvious manner until the guiding portion of the latch head guides such member into the tubular guide, 100 when this latter member will engage the yielding stop member and retard the movement of the door until the latch passes freely into the groove of the latch head, when the door will be held against closing. The office 105 of the yielding stop is to retard the movement of the door and insure the latching.

Having described my invention, I claim:

1. In a door holding device, a bracket, a rod connected thereto, a guiding bracket for 110

said rod, latch mechanism between said guiding bracket and rod, and a yielding stop comprising a sleeve, a spring within said sleeve and at one end engaging the same, 5 and an abutment on said rod for the opposite end of the spring, said parts coöperating to retard the movement of the door as the latch operation takes place.

2. In a door holding device to be applied 10 between the frame and the door, a bracket secured to one of said parts, a guiding bracket secured to the other of said parts, a rod pivotally connected to the first mentioned bracket, a head on said rod provided 15 with a latching socket, a tubular guide car-

ried by the guiding bracket and receiving the rod, a tapered guide carried by said head for guiding the same into the tubular guide, a latch carried by the tubular guide for engagement with the socket of the latching 20 head, and means for retarding the door movement as the latching operation takes place.

In testimony whereof I affix my signature in presence of two witnesses.

WILLIAM H. WOOD.
